CHANCE TICKET

Archie Jacobstein and Bessie Jacobstein,
Louisville, Ky.

Application May 6, 1938, Serial No. 206,499

1 Claim. (Cl. 283—6)

This invention relates to certain new and useful improvements in chance ticket.

The primary object of the invention is to provide a chance ticket of multi-ply construction with the top ply or wall carrying a flap or tab that is preferably die cut into the top wall before the plies are secured together, the tab being of any appropriate design with the uncut end thereof constituting a hinge while relatively small 5 tongues at opposite sides of the tab being uncut from the top wall and normally holding the tab in closed position or in the plane of the top wall for concealing a chance number or other character therebeneath.

15 A further object of the invention is to provide a chance ticket of the foregoing character in which bending of the ticket outwardly of the free end of the tab causes said free end to be raised out of the plane of the wall carrying the same 20 and in position for ready grasping for the breaking of side tongues connecting the tab to the top wall, the tongues also being of such size that the bending of the ticket automatically breaks the connecting tongues to permit opening movement 25 of the tab and exposure of the chance number or other character concealed therebeneath.

With the above and other objects in view that will become apparent as the nature of the invention is better understood, the same consists in the 30 novel form, combination and arrangement of parts hereinafter more fully described, shown in the accompanying drawing and claimed.

In the drawing:

Figure 1 is a top plan view of the chance ticket 35 constructed in accordance with the present invention, showing a tab carried by the top ply or wall of the ticket with instructions on the ticket for opening the tab;

Figure 2 is a side elevational view of the ticket 40 showing the same partially bent on a line outwardly of the free end of the tab to position said free end outwardly of the plane of the wall carrying the tab;

Figure 3 is a side edge elevational view, similar 45 to Figure 2, showing a further bending movement imparted to the ticket with the tab completely moved outwardly of the plane of the wall carrying the same;

Figure 4 is a top plan view of the ticket with 50 the tab in its fully opened position exposing a chance number or the like;

Figure 5 is a vertical cross sectional view, taken on line 5—5 of Figure 1; and

Figure 6 is a vertical cross-sectional view taken 55 on line 6—6 of Figure 2.

The chance ticket may be formed of any material desired, cardboard or the like being preferable, and the general configuration thereof may be of any desired shape, the ticket being of multi-ply construction with at least two plies as illustrated and indicated by the reference characters 10 and 11 respectively which will hereinafter be referred to as the top and bottom walls. The top and bottom walls are adhesively or otherwise secured together, but before said walls are connected, the top wall 10 is provided with a normally closed pull tab.

The pull tab 12 that may be of any desired shape and preferably of substantially oval formation in plan view, the tab 12 being preferably die cut on the line 13, with the end 14 of the tab 12 adjacent the end 15 of the ticket being uncut to constitute a hinge for the tab, the other end of the tab 12 being fully cut to form a pull end 16 with said pull end 16 spaced a considerable distance from the other end 17 of the ticket.

In the cutting of the tab 12 from the wall 10 of the ticket, spaced portions at each side thereof remain uncut to form tongues 18 for normally retaining the tab 12 in the plane of the wall 10 of the ticket.

Instructions for the use of the ticket and in the opening of the flap 12 are printed on the outer face of the top wall 10 and as shown in Figure 1, the words "lift here" together with an arrow 20 pointing toward the pull end 16 of the tab 12 are printed on said tab. A transversely extending dotted line 21 is printed on the top wall 10 of the ticket adjacent the pull end 16 of the tab and the words 22 reading "bend here" are printed on the top wall 10 below and adjacent said line 21. It is to be understood that the line 21 is not weakened, the instructions indicating that the ticket is to be bent in the proximity of the line 21.

To open the tab 12, the ticket is transversely bent in proximity of the line 21 as shown in Figure 2, to displace the pull end 16 of the tab 12 outwardly of the plane of the top wall 10 of the ticket and in position to be gripped by the user for breaking the tongue connection 18 between the tab 12 and the top wall 10 as shown in Figure 3 of the drawing. The tab 12 then being fully opened to the position shown at 12a in Figure 4 for exposing a portion 23 of the adjacent face of the bottom wall 11 that carries a chance number 24 or other identification character thereon as shown in Figure 4. It is also to be understood that the tongues 18 may be weakened to such an extent that the bending of the ticket from the position shown in Figure 2 to that position shown

in Figure 3 will automatically break the tongue connection between the tab 12 and top wall 10 for the freeing of the tab from the top wall for movement on its hinge connection 14.

5 While there is herein shown and described the preferred embodiment of the invention, it is nevertheless to be understood that minor changes may be made therein without departing from the spirit and scope of the invention as claimed.

10 We claim:

In a chance ticket, a two-ply construction comprising top and bottom walls, a tab formed in the top wall and having a hinged end and a pull end, tongues spaced from the pull end connecting the 15 sides of the tab to the top wall for normally retaining the tab in the plane of the top wall

whereby the pull end of the tab is moved outwardly of the plane of the top wall when said ticket is bent on a line transversely thereof adjacent and outwardly of said pull end to position the latter for gripping and breakage of the 5 tongues for opening the tab on its hinged end to expose the adjacent upper portion of the bottom wall, said tab being of substantially oval formation with the hinge end in proximity of one end of the ticket and the pull end terminating in 10 proximity of the transverse median line of the ticket to provide a finger gripping portion on the ticket opposite the hinged end of the tab.

ARCHIE JACOBSTEIN.
